STOP MECHANISM PARTICULARLY FOR
STRAIGHT BAR KNITTING MACHINES

George Wilders, Kegworth, and William Gordon Macdonald, Loughborough, England, assignors to William Cotton Limited, Loughborough, England

Application October 2, 1942, Serial No. 460,558
In Great Britain October 11, 1941

6 Claims. (Cl. 66—82)

This invention is concerned with Cotton's patent and other straight bar knitting machines, and is primarily but not exclusively concerned with the single section type of Cotton's patent knitting machine that has recently been evolved for knitting the heel tabs on to stocking blanks. In this machine the cam shaft is driven through a pinion mounted on and adapted to be shogged with such shaft. The male part of a dog clutch is associated with this pinion, and the female part of this clutch is mounted on or associated with the draw cam which is itself freely mounted on the shaft; when the shaft and pinion are shogged the dog clutch is engaged or disengaged according to the direction of shogging to couple the cam to or to uncouple it from the driving pinion. In order that the draw cam may be brought to a standstill, when it is uncoupled, a friction brake is associated therewith, but it has been found that this friction brake is not of itself sufficient to ensure that the draw cam always stops in the same position so that the thread carriers are located beyond the selvedge needles; variation in the angular position reached by the draw cam when it is brought to a standstill will result in the carriers being located inwards of the selvedge needles, so as to interfere with the operation of the transfer points.

The main object of the present invention is to provide simple and efficacious alternative means for achieving this result and with this and other objects in view the invention consists in a Cotton's patent or other straight bar knitting machine wherein the draw mechanism is capable of being disconnected from its driving means and there is provided a friction brake for bringing the disconnected draw mechanism to rest and positive locking means for locking the draw mechanism in a predetermined position of rest, characterised in that the positive locking means comprises a projection on a rotating part of the draw mechanism and a slidable member restrained against rotation with said rotating part but slidably movable into the path of rotation of the projection. Conveniently but not necessarily the rotating part is constituted by the cam and the projecting part projects from the side of such cam. Alternatively the projecting part projects from the side of a disc co-axially with the cam.

The foregoing and other features of the invention set out in the appended claims are incorporated in the constructions (suitable for application to a heeling machine for the purpose of ensuring the arrest of the carriers beyond the

selvedges) shown in the accompanying drawings, in which:

Figures 1 and 2 are, respectively, an end elevation and a plan of one construction, and

Figures 3 and 4 are, respectively, an end elevation and a plan of another construction.

According to one method of carrying the invention into effect as applied to single section machines of the type referred to, a bell crank lever 10 pivoted to the machine frame at 11 has a roller 12 on one arm in rubbing contact with one side face of the pinion 13 and its other arm is connected by a spring 14 to a yoke 15 the ends of which carry an arcuate brake shoe 16 coaxial with and normally displaced a short distance from the periphery of the disc cam 17 which may be attached to or formed integrally with the draw cam not shown, or may be mounted on the cam shaft 27 to rotate with the draw cam. This 15 brake is conveniently of the same width as the disc and depending radially from one edge of the brake towards the disc centre is a tongue 18 so that when the pinion 13 is shogged to disengage the dog clutch 19 the bell crank lever 10 is pivoted to apply the brake and the said tongue 18 moved towards the disc centre. When the 20 brake is off, the tongue 18 is disposed beyond the periphery of the disc 17 but when the brake is applied the tongue is moved so that part of 25 it lies inside the periphery, preferably flush with one side face of the disc and when in this position the tongue co-acts with a projection 20 formed on such side face. This projection 20 is 30 conveniently of arcuate configuration and is fixed by screws and extends from the periphery towards the disc centre for a short distance, the arrangement being such that after the brake has 35 been applied the projection 20 rotating with the disc 17, in the direction of the arrow in Fig. 1 40 abuts against the tongue 18 and the disc is thus always stopped in the same position. The aforesaid spring 14 connecting the yoke 15 to one end 45 of the cranked lever 10 is preferably a coil spring and disposed axially within it is a rod 21 of such a length that the spring is always under tension the arrangement being such that when the pinion 13 is shogged to re-engage the clutch 19 the return movement of the lever 10 under the action of such spring 14, is arrested by such rod 21 immediately prior to the final engaging movement 50 of the clutch the release movement of the brake 16 and yoke 15 being effected by two compression springs 22 each surrounding a short guiding rod 23 (the two rods being parallelly disposed) extending from a fixed part 24 and projecting

through bosses 15' formed integral with said yoke 15. Said bosses 15' are mounted for sliding movement on said rods 23 and the compression springs 22 are located between the bosses 15' and the fixed part 24 from which the rods 23 extend. The arrangement is such that the brake shoe 16 is moved to the off position and the tongue 18 is moved out of the path of the projection 20 before the clutch 19 re-engages. In an alternative construction the springs for moving the brake shoe and associated tongue to an inoperative position are dispensed with and positive means for effecting such movement are provided.

In a preferred method (Figs. 3 and 4) of carrying the invention into effect the brake mechanism is as described with reference to the first embodiment but the tongue 18 adapted to co-operate with the projection 20 for positively stopping the draw cam always in the same position is carried by a sleeve 25 slidably mounted on a pin 26 extending from the machine frame, the axis of such pin 26 being parallel with the axis of the cam shaft 27 on which the pinion 13 is fixedly mounted, and on which the draw cam and the disc 17 are rotatably mounted. The axis of the pin 26 is outside the periphery of the pinion 13 and disc 17, and a fork 28 on the sleeve 25 engages the two side faces of the pinion 13 so that as the pinion 13 is shogged in either direction the sleeve 25 is similarly shogged relatively the pin 26. A fixed guiding pin 29 is provided to prevent rotation of the sleeve. When the clutch 19 is engaged the tongue 18 occupies a position, beyond that face of the disc 17 on which the projection 20 is mounted, out of the path of movement of such projection. When the pinion 13 is shogged to disengage the clutch 19 the brake is applied by the cranked lever 10 as before-described and the tongue 18 is moved towards such face of the disc 17 into the path of movement of the projection 20 and thereby ensures that the cam is always stopped in the same position. If desired there may be two spaced projections on the disc and the tongue may be moved to occupy a position between and abutting against the opposed ends of such projections so that it inhibits movement of the cam in either direction and thereby prevents rebound. This latter arrangement is not, however, normally to be recommended. One of the main uses of the mechanism is to ensure that the thread carrier actuated through the instrumentality of the draw cam shall always stop at the end of its traverse for if the cam continues to rotate after the carriage has reached the end of its traverse the carrier commences its return motion with the result that the end needles of the selvedge are pressed off. In general, the pinion 13 will be shogged by shogging the cam shaft 27.

The positive stop mechanism described herein ensures that the carrier is stopped at the end of its traverse even though, as is usually the case with heeling machines of the type referred to, the carriers are run at comparatively high speeds and even though the brake shoe may become worn or its efficiency impaired by oil or grease. Nevertheless a small amount of rebound is not detrimental (that is to say the amount of rebound is such that the carrier will still be beyond the selvedge needle) and a feature of both types of stop mechanism described herein particularly when used with fast running machines is that consequent upon a small measure of rebound being permitted the mechanism is

less harsh on the machine and the stop mechanism is kinder in its action than it otherwise would be.

In the foregoing description of both embodiments of the invention it has been stated that the projection with which the tongue co-operates to stop the draw in a predetermined position may be a separate part attached to one side face of the disc cam. Alternatively the projection may be formed integrally with such cam and if the cam is of dished formation may be constituted by a radial rib; in this event the inner end of the tongue is provided with an inwardly directed right-angled projection for engaging said rib.

Whilst the invention has been described with particular reference to fast running straight bar knitting machines for knitting heels it will readily be appreciated that it may with advantage be applied to numerous other types of machines and for numerous different purposes.

We claim:

1. In a straight bar knitting machine of the kind having draw mechanism capable of being disconnected from its driving means and a friction brake for bringing the disconnected draw mechanism to rest; the combination with a rotatable part of the draw mechanism, of positive locking means for locking the draw mechanism in a predetermined position of rest, comprising a projection on said rotating part, a slideable member movable into and out of the path of the projection, means restraining the said member against rotation with said projection, and means for moving the said member into said path when the draw mechanism is disconnected.
2. A knitting machine according to claim 1, having the slideable member movable radially into and out of the path of the rotatable projection.
3. A knitting machine according to claim 1, having the slideable member movable axially into and out of the path of the rotatable projection.
4. In a straight bar knitting machine of the kind having draw mechanism capable of being disconnected from its driving means and a friction brake for bringing the disconnected draw mechanism to rest; the combination of a rotatable brake disc having a periphery for engagement by the friction brake, a projection on a side of said disc, a slideable member movable radially into and out of the path of the projection, means restraining the said member against rotation with said projection, and means for moving the said member into said path when the draw mechanism is disconnected.
5. In a straight bar knitting machine of the kind having draw mechanism capable of being disconnected from its driving means and a friction brake for bringing the disconnected draw mechanism to rest; the combination of a rotatable brake disc having a periphery for engagement by the friction brake, a projection on a side of said disc, a fixed axially-extending pin, a sleeve slideable thereon, a part on the sleeve movable by said sliding movement into and out of the path of the projection, and means for moving the sleeve to bring said part into said path upon application of the friction brake.
6. In a straight bar knitting machine having a shogging cam shaft and draw mechanism capable of being disconnected from its driving means, the combination of a driving pinion fast on the cam shaft, a draw cam on the cam shaft, a dog clutch for driving the draw cam from the pinion and comprising two dog members, sepa-

rable by shogging the cam shaft to disconnect the draw cam from its drive, whereof one member is connected to the draw cam and the other to the pinion, a brake disc rotatable with the draw cam, a friction brake for engaging the periphery of the brake disc, a projection on a side face of the brake disc, a member slideable into and out of the path of rotation of said projection, and connections for applying the friction

brake and for moving the last said member into the path of the projection when the pinion is shogged to disengage the dog clutch, whereof the connections for applying the brake comprise springs for resiliently transmitting the brake applying effort.

GEORGE WILDERS.
WILLIAM GORDON MACDONALD.
